UNITED STATES PATENT OFFICE.

WILLIAM E. McCOMB, OF CAMERON, MISSOURI.

MEANS FOR DISSOLVING AND SUPPLYING BOILER COMPOUNDS TO BOILERS.

1,173,365.

Specification of Letters Patent. Patented Feb. 29, 1916.

Application filed November 24, 1914. Serial No. 873,843.

To all whom it may concern:

Be it known that I, WILLIAM E. McCOMB, a citizen of the United States, residing at Cameron, in the county of Clinton and State of Missouri, have invented a new and useful Means for Dissolving and Supplying Boiler Compounds to Boilers, of which the following is a specification.

This invention has reference to means for supplying boiler compounds to boilers, and its object is to provide a means whereby feed water may be driven through a vessel containing the compound in a manner to cause the ready solution of the soluble parts 15 of the compound and the direction of the compound so dissolved to the boiler.

In accordance with the present invention there is provided a cylinder into which the compound is introduced, and this cylinder 20 is entered at one end by a pipe connected to the hot water pump or injector supplying water to the boiler. The cylinder has an outlet so arranged that water driven into the cylinder has no direct path to the outlet, but must follow a more or less tortuous route, whereby compound placed in the cylinder is thoroughly agitated and the soluble parts thereof are readily dissolved. In the 25 line of travel of the solution from the dissolving chamber the solution passes through a mixing flow and pressure cylinder, after which it is conducted to the boiler. The two cylinders are arranged in a by-pass connected to the main supply pipe, in which 30 latter there is located a valve, while the by-pass also contains valves whereby the flow of water is regulated as desired. The arrangement also is provided with washing inlets and outlets and requisite valves for 35 controlling the course of the fluids employed.

The invention will be best understood from a consideration of the following detailed description, taken in connection with 40 the accompanying drawing, forming a part of this specification, with the further understanding that while the drawing shows a practical form of the invention, the latter is not confined to any strict conformity with 45 the showing of the drawing, but may be changed and modified so long as such changes and modifications mark no material departure from the salient features of the 50 invention.

55 In the drawing, the figure is a view partly in elevation and partly in section, showing

an arrangement employed in accordance with the present invention.

In the drawing there is shown a pipe 1 which may be considered as connected at one end to the hot water pump or injector of the boiler, and at the other end to the boiler itself. This pipe includes two T connections 2, 3, respectively, at suitably spaced points, and between these T connections is a cut-off valve 4 which may be of the usual globe type, or of any other desired type. Leading from the T 2 is another pipe 5 including a cut-off valve 6 which may also be of the globe type, and a check valve 7 which may be of any suitable known form. The pipe 5 terminates in an elbow 8 connected to one end of a T 9, while the other end of this T communicates through a cut-off valve 10 shown as of the globe type, with a pipe 11 extending through one head 12 of a cylinder 13 and entering said cylinder for a distance which may be about two-thirds of the length of the cylinder, the latter being usually arranged in an upright position.

In describing the various pipes and their communications with the valves, it will be understood that nipples or other fittings are used wherever needed, but no special reference is made to such commonly used parts or pipe fittings.

The cylinder 13 has the end remote from the end 12 closed by another head 14 provided with an inlet passage 15 normally closed by a screw plug 16. Extending through the head 14 is a pipe 17, which for convenience of assemblage may be made of two parts, and this pipe within the cylinder terminates in a T 18 carrying two branch pipes 19 on opposite sides of the pipe 11 and opening at a lower level than the top of the pipe 11. The pipe 17 includes a controlling valve 20 which may be a globe valve, and opens into a cylinder 21 through one head 22 thereof. The other head 23 of this cylinder is connected by a pipe 24 to a T 25 to one end of which is connected the corresponding end of a pipe 26 in turn connected at the other end to the T 3. The pipe 26 includes a valve 27, which like the other valves may be of the ordinary globe type. Branched off from the T 25 on the end of the latter remote from the pipe 26 is another pipe 28 including a controlling globe valve 29.

Branched off from the T 9 is a pipe 30 terminating in another T 31 from which

there is branched another pipe 32 including a controlling valve 33. Also proceeding from the T 31 is a pipe 34 including a valve 35 and entering the cylinder 13 through the head 12. Inside of the cylinder 13 the pipe 34 has an elbow 36 connected thereto and immediately beyond this elbow the pipe terminates, the terminal portion of the pipe being substantially horizontal and quite close to the bottom head 12 of the cylinder 13.

A suitable compound or composition indicated at 37 is introduced into the cylinder 13 on the removal of the plug 16, which is afterward replaced. This compound may consist of soda ash, caustic soda, and graphite, or any other material or materials employed in connection with boilers for dissolving deposits and for other purposes.

Let it be assumed that the valves 6 and 27 are closed and the valve 4 is open. Under these circumstances water from the hot water pump or injector flows directly to the boiler. If it be desired to introduce the compound into the boiler, assuming that the materials of the compound are already within the cylinder 13, the valves 6, 10, 20 and 27 are opened to such extent as may be desired, and the valve 4 is closed to such extent as may be needful. The valves 29, 33 and 35 are assumed to be closed. Now hot water from the hot water pump or injector flows through the pipe 1 to the T 2, thence by way of the pipes 5 and 11 to the cylinder 13, and issues from the upper end of the pipe 11 into the cylinder 13. Water accumulates in the cylinder 13, acting on the compound 37 and ultimately reaching the entering ends of the branch pipes 19 and, under the pressure employed, the water may ultimately reach a considerable height within the cylinder 13, such, for instance, as indicated by the dotted line 38. The water entering the cylinder 13 through the pipe 11 finding no direct escape therefrom, and of necessity flowing downwardly before it can reach the entering ends of the branch pipes 19 engages the compound 37, and thoroughly agitates and dissolves it, and also carries some of the material, such as the insoluble graphite, with it, into the pipes 19. The solution and such of the compound as may be insoluble flows into the cylinder 21 into which may be carried any small particles of the compound agitated by the opening of the valve 35. Such particles settle in the cylinder 21 and hence do not reach the valve 27 as might occur if the cylinder 21 were not present. Should such particles reach the valve 27 they would be liable to clog it.

Thence the water carrying the compound passes by way of the pipe 26 to the T 3 and ultimately reaches the boiler. If the valve 4 be wholly closed, then the entire flow of feed water passes through the pipe 5, cylinder

13, cylinder 21 and pipe 26 to the boiler. If the valve 4 be partly open and the valves in the branch pipes be properly regulated any degree of proportionate flow may be established between the main pipe 1 and the branch or by-pass pipes. The air trapped within the cylinder 13 between the level 38 of the water therein and the top of the cylinder constitutes an air cushion which equalizes the flow of the solution. By closing the valve 27 and opening the valve 29 to the desired extent, the compound or water alone will flow out from the open end of the pipe 28, so that it is easy to ascertain the density of the solution and also whether or not the compound is all dissolved. By opening the valve 35 there is provided a path for the feed water through the pipe 34, and this water entering the cylinder 13 stirs up any compound 37 which may be therein. By closing the valve 10 and opening the valves 33 and 35 with the pipe 32 suitably connected to a source of fluid under pressure, it is possible to blow or wash out the whole structure.

With a structure such as shown in the drawings in which the pipe 1 is a one inch pipe and the by-pass pipes 5 and 26 are three-eighth inch pipes, four pounds of soda ash placed in the cylinder 13 have been injected into the boiler in less than an hour. Again, by a suitable adjustment of the various valves, the injection of the compound may be prolonged for eighteen to twenty-four hours.

In the handling of graphite it is quite feasible to keep it agitated as by the pipe 34, so that there is no chance for the graphite to settle to the bottom of the cylinder 13.

While in the foregoing example certain sizes of pipes have been mentioned, it will be understood that the invention is not limited to any particular sizes of pipes, for in these features it is possible to vary the proportions through relatively wide limits.

In a practical form of the invention a cylinder 13 as long as eighteen inches has been used with the cylinder 21 about ten inches in length, but here again the proportions given are not to be taken as limiting the invention in its practical form to any such particular proportions.

The cylinder 21 is included in the line of piping between the cylinder 13 and the boiler to catch and cause any particles of the compound reaching it to dissolve so as to prevent them from reaching and clogging the valve 27. Such carrying along of the compound is liable to occur when the compound in the cylinder 13 is agitated by opening the valve 35.

What is claimed is:—

1. A means for injecting compounds into boilers, comprising a main pipe for feeding water, a valve therein, and a pipe line branched around the valve in the main pipe

and including an upright chamber or receptacle for the compound, with a part of the branch pipe entering the receptacle and opening upwardly therein at a relatively high point, and that portion of the branch pipe leaving the receptacle opening downwardly therein at a lower point sufficiently above the bottom of the receptacle to provide room for the compound below said outlet pipe, and said branch pipe line being provided with valves for the regulation of the flow therethrough.

2. A means for injecting compounds into boilers, comprising a pipe leading to the boiler and including a valve, a pipe branched off from the first-named pipe to one side of the valve, a chamber into which the branch pipe rises and in which it terminates, another pipe leading from the chamber from a lower level than the top of the first-named pipe, another chamber into which the second-named pipe leads, and a third pipe leading from the second chamber to the first-named pipe at the other side of the valve in the first-named pipe.

3. A means for injecting compounds into boilers, comprising a pipe leading to the boiler and including a valve, a pipe branched off from the first-named pipe on one side of the valve, a chamber into which the branch pipe leads and in which it terminates, another pipe leading from the chamber from a lower level than the discharge end of the first-named pipe, another chamber in which the second-named pipe leads, and a third pipe leading from the second chamber to the first-named pipe at the other side of the valve in the first-named pipe, the branch pipes including valves for the control of flow therethrough.

4. A means for feeding compounds to boilers comprising a main feed pipe having a valve therein, a branch pipe leading therefrom and including spaced valves and a check valve between them, a cylinder into which the branch pipe discharges at a high point therein, means for permitting access to the cylinder for the introduction of boiler compound thereinto, a valved pipe leading from the second-named pipe between the valves therein and entering the bottom portion of the cylinder, another pipe leading from the cylinder from a low point therein and containing a valve, another cylinder into which the last-named pipe enters, and still another pipe leading from the second-named cylinder to the first-named pipe on the other side of the valve therein and also containing a flow controlling valve.

5. A means for feeding compounds to boilers comprising a main feed pipe having a valve therein, a branch pipe leading therefrom and including spaced valves and a check valve between them, a cylinder into which the branch pipe discharges at a high

point therein, means for permitting access to the cylinder for the introduction of boiler compound thereinto, a valved pipe leading from the second-named pipe between the valves therein and entering the bottom portion of the cylinder, another pipe leading from the cylinder from a low point therein and containing a valve, another cylinder into which the last-named pipe enters, and still another pipe leading from the second-named cylinder to the first-named pipe on the other side of the valve therein and also containing a flow controlling valve, the last-named pipe having a valved outlet on the side of the valve in said last-named pipe remote from the first-named pipe.

6. A means for introducing boiler compound into boilers, comprising a valved pipe for the passage of feed water to the boiler, and a branch pipe connected at opposite ends to the first-named pipe around the valve therein, said branch pipe including a compound receptacle within which the continuity of the branch pipe is broken with the ends of the branch pipe within the receptacle at different levels, and valves for controlling the flow of water through the branch pipe and the receptacle included therein, said branch pipe having another pipe branched therefrom and opening into the receptacle at a low level therein and provided with a valve for the control of fluid therethrough.

7. A means for introducing boiler compound into boilers, comprising a valved pipe for the passage of feed water to the boiler, and a branch pipe connected at opposite ends to the first-named pipe around the valve therein, said branch pipe including a compound receptacle within which the continuity of the branch pipe is broken with the ends of the branch pipe within the receptacle at different levels, and valves for controlling the flow of water through the branch pipe and the receptacle included therein, said branch pipe having another pipe branched therefrom and opening into the receptacle at a low level therein and provided with a valve for the control of fluid therethrough, and said last-named pipe having a valved pipe connected thereto for directing wash fluid into the receptacle.

8. A means for introducing boiler compound into boilers, comprising a valved pipe for the passage of feed water to the boiler, and a branch pipe connected at opposite ends to the first-named pipe around the valve therein, said branch pipe including a compound receptacle within which the continuity of the branch pipe is broken with the ends of the branch pipe within the receptacle at different levels, and valves for controlling the flow of water through the branch pipe and the receptacle included therein, said branch pipe having another

4

pipe branched therefrom and opening into the receptacle at a low level therein and provided with a valve for the control of fluid therethrough, and said last-named pipe 5 having a valved pipe connected thereto for directing wash fluid into the receptacle, the pipe also including another receptacle in the portion of the branch pipe after leaving the first-named receptacle, and a valved outlet 10 from the pipe after leaving the second-named receptacle.

9. In a means for introducing boiler compound into boilers, a compound receptacle, a water pipe leading thereinto and terminating at a high point in said receptacle, 15 and a pipe leading therefrom and communicating with the interior of the receptacle at a lower point than the inlet pipe, said receptacle also having means for the introduction of an agitating stream of water at a low point therein.

10. In a means for dissolving and introducing boiler compound into boilers, a receptacle for the compound having a water 25 pipe leading thereinto and opening within the receptacle at a high point therein, another pipe leading from and branched within the receptacle and communicating with said receptacle at a relatively low point 30 therein, said receptacle being also provided with another pipe entering it at a low point

and having means of communication with both the inlet water pipe of the receptacle and with other fluid under pressure for either agitating the compound introduced 35 into the receptacle or conveying wash or blow out fluid thereto.

11. In a means for introducing boiler compound into boilers, a normally closed receptacle for compounds provided with removable means for permitting introduction of the compound, a water pipe entering the receptacle and opening therein at a relatively high point, and an outlet pipe entering the receptacle to a relatively low point, 40 and terminating at a distance above the bottom of the receptacle to provide room below the outlet pipe for a mass of compound, whereby water passing through the receptacle is constrained to follow an indirect 45 path and engage the compound for dissolving the latter, and air is entrapped in the receptacle to form an elastic cushion for equalizing the outflow from the receptacle.

In testimony, that I claim the foregoing 55 as my own, I have hereto affixed my signature in the presence of two witnesses.

WILLIAM E. McCOMB.
